Primary Examiner — Melody N Brown(74) *Attorney, Agent, or Firm* — Plumsea Law Group, LLC(57) **CLAIM**

The ornamental design for an automobile and/or replica thereof, as shown and described.

DESCRIPTION

FIG. 1 is a front perspective view of an automobile and/or replica thereof showing our new design;
FIG. 2 is a rear perspective view thereof;
FIG. 3 is a front elevational view thereof;
FIG. 4 is a rear elevational view thereof;
FIG. 5 is a top plan view thereof;
FIG. 6 is a side elevational view of one side thereof; and,
FIG. 7 is a side elevational view of the opposite side thereof. The broken line portions of the vehicle shown throughout the drawing views are for illustrative purposes only and form no part of the claimed design.
